GLASS DRYING APPARATUS

James E. Starner, Toledo, Ohio, assignor to
 Libbey-Owens-Ford Glass Company, Toledo,
 Ohio, a corporation of Ohio

Application August 23, 1947, Serial No. 770,259

5 Claims. (Cl. 15—306)

1

The present invention relates broadly to glass cleaning apparatus and more particularly to an apparatus for drying bent or curved sheets or plates of glass.

An important object of the invention is the provision of improved apparatus wherein the efficient drying of bent glass sheets or plates of different curvatures may be accomplished rapidly and conveniently in a substantially continuous manner as the said sheets or plates are carried forwardly on edge in a substantially vertical position.

Another object of the invention is the provision of improved apparatus of the above character embodying novel means for supporting the glass sheets which will enable the entire surfaces of said sheets to be thoroughly dried as the said sheets are carried forwardly.

A further object of the invention is the provision of improved apparatus of the above character embodying novel means for effecting a complete and uniform drying of all portions of the surfaces of the glass sheets regardless of the curvature of said sheets as they travel forwardly.

A still further object of the invention is the provision of drying apparatus of the above character of relatively simple, inexpensive construction and embodying means for supporting the bent or curved sheets of glass in a substantially vertical position and for carrying them continuously forwardly during drying without placing any strain upon the glass whereby breakage thereof will be reduced to a minimum, said supporting means presenting substantially no interference to the proper drying operations.

Other objects and advantages of the invention will become more apparent during the course of the following description, when taken in connection with the accompanying drawings.

In the drawings wherein like numerals are employed to designate like parts throughout the same:

Fig. 1 is a front elevation of apparatus constructed in accordance with the invention;

Fig. 2 is a plan view thereof;

Fig. 3 is a vertical transverse section taken substantially on line 3—3 of Fig. 1, illustrating the washing means;

Fig. 4 is a vertical transverse section taken substantially on line 4—4 of Fig. 1, illustrating the rinsing means;

Fig. 5 is a side view of the drying means;

Fig. 6 is a detail sectional view through one of the tubular washing elements showing the details of the tube cleaning member;

2

Fig. 7 is an enlarged view of a part of the sheet conveyor and support for the drying means; and

Figs. 8, 9 and 10 are diagrammatic views which illustrate the operation of the drying means as a curved sheet of glass passes therethrough.

Generally stated, in carrying out the invention, the bent or curved sheets or plates of glass to be cleaned are placed upon one end of a conveyor and carried successively through washing, rinsing and drying zones. During conveyance through the washing zone, the sheets are supported on edge in a substantially vertical position by horizontal endless belts having relatively narrow sheet contacting surfaces. The supporting belts in the washing zone are arranged at different levels, so that different areas of the sheets are engaged by the belts to assure that the entire sheet surfaces are exposed to the washing fluid. The glass sheet passes from the washing zone through a rinsing zone into a drying zone. The drying of the sheet surfaces is accomplished by a pair of blower pipes carried by a pivotally mounted framework. The framework is provided with supporting surfaces along which the curved glass sheet moves and, by reason of the novel pivotal support, the blower pipes are caused to follow the curvature of the glass sheet to thoroughly remove the moisture from each surface thereof. Upon passage of the sheet from the drying zone, the framework is automatically returned to its normal position to receive the leading edge of a subsequent sheet without requiring adjustment for any particular type of bend.

Referring now to the drawings, there is illustrated a tunnel-type housing, generally indicated at 10, which is divided into a washing zone or compartment 11 and a rinsing zone or compartment 12. Extending from opposite ends of the housing 10 are horizontal track supporting frames 13 and 14; the frame 13 being arranged at the entrance end of the washing compartment 11 to receive the glass sheets 15 to be cleaned, while the frame 14 is arranged at the exit end of the rinsing compartment 12 for supporting the glass sheets as they are removed to a point of inspection and packing.

A horizontal endless conveyor 16, preferably in the form of a conventional sprocket chain, is supported on track forming channels 17 and is trained about suitable sprocket wheels 18 and 19 located at the outer ends of frames 13 and 14. The sprocket wheels 18 and 19 are carried by transversely disposed shafts 20 and 21 respectively, journaled in bearing blocks 22 secured to the respective frames 13 or 14. One of the

shafts, as shaft 21, provides driving power for the conveyor chain 16 by a suitable sprocket 23 keyed thereon and operatively connected to a power transmission unit 24 by a chain belt 25.

The motor 26 for driving the transmission unit 24 may be manually controlled by a hand switch 27 or caused to stop automatically upon opening of a normally closed limit switch 28 mounted near the outer end of the frame 14. Preferably, the switch 28 is provided with an actuating bar 29 engageable by the glass sheet 15 in the event the sheet is not removed by an operator before reaching the end of the frame 14. Without such automatic control means, the glass sheets might fall from the end of the conveyor line.

The conveyor chain 16 is provided at regularly spaced intervals with sheet supporting blocks 30 of rubber, or other suitable material, having a step 31 formed thereon for receiving the lower edges of the glass sheets 15 (Fig. 3). The blocks 30 cooperate with a plurality of freely rotatable rollers 32 which engage the rear surfaces of the glass sheets 15 for supporting the said sheets in a substantially vertical position at the entrance and exit ends of the machine, said rollers 32 being mounted in vertically spaced, horizontal rows on the angles 33 forming a portion of the frames 13 and 14.

During travel of the glass sheets through the washing and rinsing compartments 11 and 12, they are maintained in a similar position by pairs of longitudinally extending, horizontal belts 34, 34', and 35. The pairs of belts 34 and 34' in washing compartment 11 are trained about sheaves 36, 36', and 37, while the pair of belts 35 in rinsing compartment 12 is trained about sheaves 38 and 39, in order that they may be driven at a comparable rate of speed to the conveyor chain 16 to adequately support the sheets during the washing and rinsing operations. The belts 34, 34' and 35 are driven from a common jack shaft 40 extending longitudinally along the top of the housing 10 and journalled in bearings 41. The shaft 40 is coupled to a second longitudinally extending shaft 42 mounted in bearings on the frame 14, by sprockets 43 and power transmitting chain 44 (Fig. 4), the shaft 42 being rotatively connected to and driven from the shaft 21 by bevel gears 45. The jack shaft 40 is thus driven from a common source of power with the conveyor chain 16 and will drive vertical shafts 46 and 47 carrying sheaves 36 and 38 respectively through pairs of bevel gears 48. The idler sheaves 36', 37 and 39 are carried by stub shafts 49 journalled in brackets 50 (Fig. 4) and, if desired, additional idlers 51 may be interposed in the return flights of the belts to provide a suitable tensioning means.

The shafts 46 and 47 are mounted in bearings, generally indicated at 52, attached to the frame of the housing, and depend downwardly into the compartments 11 and 12 to drive the pairs of belts 34, 34' and 35 trained about the sheaves 36, 36', 37, and 38 and 39 respectively. The pairs of belts 34 and 34' engage the glass sheets 15 in their travel through the washing zone 11 while the pair of belts 35 support the sheets in their travel through the rinsing zone 12.

To facilitate the washing of the entire surfaces of the glass sheets, the belts 34 and 34' are arranged at different horizontal levels in the washing compartment 11. Thus, as best shown in Fig. 1, the belts 34 in the preliminary washing area of the compartment 11 will contact the glass sheets in a relatively higher plane than the belts

34' in the final washing area. In this way, those portions of the glass sheets contacted by the belts 34 in the preliminary washing area will be exposed to the washing operation in the final washing area.

The washing operation, conducted in compartment 11, subjects opposite surfaces of the glass sheets to the cleansing effect of a scouring agent held in water suspension. It has been found that 10 a desired quality of scouring and cleansing may be obtained through the use of finely comminuted shell flours, such as those procured by the milling of walnut, palm nut, or the like, to a degree of particle size that can be graded through 80 mesh 15 screens. The cleansing solution is moved in a continuous system by a suitable motor driven pump 53 connected at the suction side to a reservoir tank 54 as at 55, and at the pressure side to a manifold 56 by a pipe 57. Leading from 20 the manifold 56 to points within the compartment 11 are branch pipes 58 connected to distributor pipes 59 and 60 disposed in parallel relation along opposite sides of the conveyor 16. The distributor pipes 59 and 60 are provided with a 25 plurality of upwardly inclined, parallel spray tubes 61 between which the sheets are carried by the conveyor 16. The spray tubes 61 are provided with orifices 62 through which the cleansing solution is directed against opposite surfaces of 30 the glass sheets.

To prevent plugging of the spray orifices 62 by slowly gathering accumulations of the nut flour, in suspension, a rotary self-clearing member 63 is located in each of the spray tubes 61 as shown in Fig. 6. Each clearing member 63 comprises a spirally twisted strip 64, located in and extending between the ends of the tube. The lower end of the strip 64 is supported on a pin 65 rotatably seated in a block 66 welded to the 40 distributor pipe 59 or 60. The upper end of the spirally twisted strip 64 has secured thereto the shaft 67 of a water wheel 68 and in order to suitably cap the end of the tube 61, the shaft 67 extends through a packing gland 69 so that 45 the necessary effect of the solution under pressure will be expended in a spray from the orifices 62 of the tube.

Connected to the distributor pipes 59 and 60, adjacent each of the spray tubes 61 is a feeder tube 70 having a bent upper end portion 71 directed toward the water wheel 68. The pressure of the cleansing solution is thus urged into both tubes 61 and 70 and from the tubes 61 through the orifices 62 to afford a finely divided flushing spray directed upon the glass sheets while the solution stream from the tubes 70 impinges on the vanes or paddles 72 of the water wheels 68 to cause rotation of the spiral strips 64 within tubes 61. Thus, while the washing operation is being performed, the pressure of the solution also provides a continuous self-clearing action within the tubes 61 since, as the water wheels 68 revolve, the edges 73 of the strip 64 will be carried past the inner ends of the orifices 62 and any plugging thereof will be prevented.

The washing compartment 11 of the housing 10 is closed at each end by partitions 74 which are slotted to permit passage of the glass sheets therethrough, while the bottom of said compartment is provided with a sloping drain pan 75 having a centrally located outlet through which the washing solution returns to the tank 54. In the construction shown, the top of the tank 54 is substantially open with the contained liquid 70 being protected from foreign particles, and from

particles of glass when a sheet is inadvertently broken, by a screen 76. The pressurized spray of cleansing solution directed against the surfaces of the glass sheet will effectively remove all soil accumulations and continuous movement will carry the curved sheets progressively through the washing zone, the force and direction of the multiple spray combining with the glass travel to effectively and thoroughly flush the glass surfaces.

Upon passage through the slotted end panels 14, the glass sheets 15 enter the rinsing compartment 12 where they are received on the pair of belts 35. The rinse compartment is preferably closed at the top and back by the panels 76 and 77 of the housing 10 to confine the water sprays directed upon opposite surfaces of the glass sheets from a pair of substantially parallel, vertically inclined spray pipes 78. A sloping basin shaped bottom 79 communicates with the usual sump through a discharge pipe 80. In actual practice, with this type of apparatus, it has been found preferable to omit any enclosing panel from the front of the washer along which the operation is observed.

The water rinse pipes 78 are supplied from a feed pipe 81 which is also provided with an extension 82 running to a spray nozzle 83 having a widened orifice 84. The spray nozzle 83 is positioned to direct a discharge of water toward the upper edge of the glass sheet and rearwardly at an angle as shown in Fig. 1, thereby causing the moving sheet, or sheets of glass, to pass through a "curtain" of water to further flush the surfaces.

As the glass sheet 15 emerges from the rinse compartment 12, the opposite surfaces thereof are subjected to a blast of air which acts to dry the sheet surfaces. The direction of the blast toward each side of the sheet causes the remaining surface water to be blown in the general direction of the chamber 12. Thus, the glass sheet emerging from the rinse compartment 12 onto the track support frame 14 is subjected to the action of an air blast head designated in its entirety by the numeral 85. The blast head comprises generally a frame 86 and a pair of perforated air pipes 87 and 88, pivotally carried by the vertical shaft 41. More specifically, the frame 86 has mounting collars 89, surrounding the shaft 41 at points above and below the sheaves 38, with upper and lower rails 90 extending from the collars to a point of attachment to the spray pipe 81. The frame is completed by a vertically extending rib 91 connecting the rails 90 at a point adjacent the collars. The pipe 87 extends upwardly from the upper frame rail 90 to a manifold block 92 to which the spray pipe 83 is connected at its upper end. A supply pipe 93 for air under pressure is connected to the manifold block 92 through the flexible tubing 94.

Disposed in parallel relation between the upper and lower rails 90 are a plurality of horizontally arranged rollers 95 rotatably supported on bars 96 secured at their opposite ends to the pipe 87 and rib 91. The rollers 95 are engaged by the glass sheet 15 as it leaves the rinsing compartment 12 and, in the embodiment of the invention herein set forth, are urged by a spring 97 acting on the frame 86 into the path of the oncoming sheet. The frame 86 is therefore normally maintained in the path of travel of the glass sheets by the spring 97 attached to the frame of the housing 10 and to the manifold block 92. The air pipes 87 and 88 depend from the manifold block 92 in parallel relation and

in such relation to the rollers 95 that the glass sheet passing therebetween will be maintained substantially equidistant from said pipes.

As pointed out above, the apparatus herein provided is particularly adapted for the washing of bent or curved glass sheets or plates. It will be apparent that the leading and/or rear edges of the sheets will rise from the generally supported plane and would normally tend to 5 collide with the pipes 87 and 88 as the sheets pass from the rinsing compartment. The gradually changing contour of the sheet also prevents any permanent positioning of the pipes 87 and 88 since, in such case, an equal distribution 10 of air pressure upon all portions of the sheet surfaces could not be attained. The blast head 85 will thus be caused to move rearwardly by the sheet as the curvature thereof progressively changes and will be returned to its normal position by the spring 97 as the sheet passes along 15 the frame 14 toward the end thereof. Such progressive swinging of the frame 86 is shown in Figs. 8, 9 and 10 wherein the bent sheet of glass 15 is shown in Fig. 8 as initially contacting rollers 20 95 to move the frame 86 rearwardly to cause the pipes 87 and 88 to be moved from their positions in the path of travel of the glass sheet to a position at which the leading edge of the sheet will 25 pass safely therebetween as shown in Fig. 9 and 30 wherein the surfaces of the sheet will be substantially equally spaced from the pipes 87 and 88. As the sheet continues to move between the pipes 87 and 88, the spring 97 will automatically urge the frame 86 forwardly as shown in Fig. 10. 35 Thus, the frame is caused to move rearwardly and then forwardly depending upon the curvature of the glass sheet, and in such manner that as different portions of the sheet pass between the pipes 87 and 88, the said pipes will be maintained 40 substantially equidistant from the sheet surfaces to effect a uniform application of pressure fluid upon all portions of the sheet to effect uniform and efficient drying thereof.

To prevent the glass sheets from falling from the end of the conveyor sheet 16, the limit switch 45 28 will be actuated by the sheet and cause to break the circuit through the motor 26 operating the transmission unit 24, thereby bringing the conveyor to a stop.

From the above, it will be readily seen that with the apparatus herein provided, the handling of glass sheets or plates, particularly when bent or curved, during washing and drying, is reduced to a minimum. Also, that the apparatus is of 50 relatively simple construction and that it can be operated rapidly and conveniently to effect a thorough and efficient washing and drying of the glass. While the invention is particularly adapted for the washing of glass sheets or plates, it will be apparent that the apparatus may be 55 used for the treatment of sheets of other materials.

It is to be understood that the form of the invention herewith shown and described is to be 60 taken as the preferred embodiment of the same, and that various changes in the shape, size and arrangement of parts may be resorted to without departing from the spirit of the invention or the scope of the subjoined claims.

I claim:

1. In apparatus for drying curved sheets or plates of glass or the like, means for supporting a curved glass sheet on edge in an inclined substantially vertical position and for carrying it forwardly edgewise in a substantially straight horizontal path through a drying zone, a frame

pivotedly mounted for swinging movement toward and away from the path of travel of the sheet, air supplying means carried by the frame for directing blasts of air against opposite surfaces of the sheet, said means comprising spaced perforated pipes between which the sheet passes during the drying operation, means also carried by the frame for substantially aligning the space between said pipes with the leading edge of the curved glass sheet, and spring means associated with the air supplying means for maintaining the spaced pipes predetermined, substantially equal distances from opposite surfaces of the sheet as said sheet continues along the horizontal path.

2. In apparatus for drying curved sheets or plates of glass or the like, means for supporting a curved glass sheet on edge in an inclined substantially vertical position and for carrying it forwardly edgewise in a substantially straight horizontal path through a drying zone, a frame pivotally mounted for swinging movement toward and away from the path of travel of the sheet, air supplying means normally maintained in the path of travel of the sheet, said means comprising spaced perforated pipes carried by the frame and between which the glass sheet passes for directing blasts of air against opposite surfaces of the sheet, means also carried by the frame and operative upon engagement with the sheet for urging the space between the pipes into substantial alignment with the leading edge of said sheet, and spring means associated with the air supplying means for maintaining the spaced pipes predetermined, substantially equal distances from opposite surfaces of the sheet as said sheet continues along the horizontal path and for returning said pipes into the path of travel of the sheet after said sheet has been acted upon by the air supplying means, said aligning means causing pivotal movement of the frame from a position inclined to the horizontal path of travel of the sheet to a position substantially parallel to said path.

3. In apparatus for drying curved sheets or plates of glass or the like, means for supporting a curved glass sheet on edge in an inclined substantially vertical position and for carrying it forwardly edgewise in a substantially straight horizontal path through a drying zone, a frame pivotally mounted for swinging movement toward and away from the path of travel of the sheet, air supplying means comprising inclined, spaced and perforated pipes carried by the frame for directing blasts of air against opposite surfaces of the sheet, roller means also carried by the frame and operative upon engagement with the sheet for substantially aligning the space between the pipes with the sheet, and spring means resisting the action of the roller means and associated with the air supplying means for maintaining the spaced pipes predetermined, substantially equal distances from opposite surfaces of the sheet as said sheet continues along the horizontal path.

4. In apparatus for drying curved sheets or plates of glass or the like, means for supporting a curved glass sheet on edge in an inclined substantially vertical position and for carrying it forwardly edgewise in a substantially straight horizontal path through a drying zone, a frame

pivotedly mounted for swinging movement toward and away from the path of travel of the sheet, air supplying means carried by the frame including a pair of inclined substantially parallel perforated pipes normally maintained in the path of travel of the sheet for directing blasts of air against opposite surfaces of said sheet, said pipes being spaced from one another to provide an open portion through which the sheet passes during the drying operation, roller means also carried by the frame and operative upon engagement with the sheet for urging the pipes away from the path of travel of the sheet and the open portion therebetween into substantial alignment with the leading edge of the sheet, and spring means resisting the action of the roller means and associated with the air supplying means for maintaining the pipes predetermined, substantially equal distances from opposite surfaces of the sheet as said sheet passes therebetween and for returning the pipes into the path of travel of the sheet.

5. In apparatus for drying curved sheets or plates of glass or the like, means for supporting a curved glass sheet on edge in an inclined substantially vertical position and for carrying it forwardly edgewise in a substantially straight horizontal path through a drying zone, a frame pivotally mounted for swinging movement toward and away from the path of travel of the sheet, air supplying means carried by the frame including a pair of inclined substantially parallel perforated pipes normally maintained in the path of travel of the sheet for directing blasts of air against opposite surfaces of said sheet, said pipes being spaced from one another to provide an open portion through which the sheet passes during the drying operation, roller means also carried by the frame and operative upon engagement with the sheet for urging the pipes away from the path of travel of the sheet and the open portion therebetween into substantial alignment with the leading edge of the sheet, and spring means resisting the action of the roller means and associated with the air supplying means for maintaining the pipes predetermined, substantially equal distances from opposite surfaces of the sheet as said sheet passes therebetween and for returning the pipes into the path of travel of the sheet.

30 6. In apparatus for drying curved sheets or plates of glass or the like, means for supporting a curved glass sheet on edge in an inclined substantially vertical position and for carrying it forwardly edgewise in a substantially straight horizontal path through a drying zone, a frame pivotally mounted for swinging movement toward and away from the path of travel of the sheet, air supplying means carried by the frame including a pair of inclined substantially parallel perforated pipes normally maintained in the path of travel of the sheet for directing blasts of air

35 against opposite surfaces of said sheet, said pipes being spaced from one another to provide an open portion through which the sheet passes during the drying operation, roller means also carried by the frame and operative upon engagement with the sheet for urging the pipes away from the path of travel of the sheet and the open portion therebetween into substantial alignment with the leading edge of the sheet, and spring means resisting the action of the roller means and associated with the air supplying means for maintaining the pipes predetermined, substantially equal distances from opposite surfaces of the sheet as said sheet passes therebetween and for returning the pipes into the path of travel of the sheet.

40 7. In apparatus for drying curved sheets or plates of glass or the like, means for supporting a curved glass sheet on edge in an inclined substantially vertical position and for carrying it forwardly edgewise in a substantially straight horizontal path through a drying zone, a frame pivotally mounted for swinging movement toward and away from the path of travel of the sheet, air supplying means carried by the frame including a pair of inclined substantially parallel perforated pipes normally maintained in the path of travel of the sheet for directing blasts of air

45 against opposite surfaces of said sheet, said pipes being spaced from one another to provide an open portion through which the sheet passes during the drying operation, roller means also carried by the frame and operative upon engagement with the sheet for urging the pipes away from the path of travel of the sheet and the open portion therebetween into substantial alignment with the leading edge of the sheet, and spring means resisting the action of the roller means and associated with the air supplying means for maintaining the pipes predetermined, substantially equal distances from opposite surfaces of the sheet as said sheet passes therebetween and for returning the pipes into the path of travel of the sheet.

50 8. In apparatus for drying curved sheets or plates of glass or the like, means for supporting a curved glass sheet on edge in an inclined substantially vertical position and for carrying it forwardly edgewise in a substantially straight horizontal path through a drying zone, a frame pivotally mounted for swinging movement toward and away from the path of travel of the sheet, air supplying means carried by the frame including a pair of inclined substantially parallel perforated pipes normally maintained in the path of travel of the sheet for directing blasts of air

55 against opposite surfaces of said sheet, said pipes being spaced from one another to provide an open portion through which the sheet passes during the drying operation, roller means also carried by the frame and operative upon engagement with the sheet for urging the pipes away from the path of travel of the sheet and the open portion therebetween into substantial alignment with the leading edge of the sheet, and spring means resisting the action of the roller means and associated with the air supplying means for maintaining the pipes predetermined, substantially equal distances from opposite surfaces of the sheet as said sheet passes therebetween and for returning the pipes into the path of travel of the sheet.
